UNITED STATES PATENT OFFICE.

GRÄFIN MARIA VON LINDEN, OF BONN, ERNST MEISSEN, OF HOHENHONNEF, NEAR BONN, AND ARTUR STRAUSS, OF BARMEN, GERMANY, ASSIGNEES TO FARBENFABRIKEN VORM. FRIEDR. BAYER & CO., OF ELBERFELD, GERMANY, A CORPORATION OF GERMANY.

PHARMACEUTICAL COMPOUND.

1,072,745.

Specification of Letters Patent.

Patented Sept. 9, 1913.

No Drawing.

Application filed February 11, 1913. Serial No. 747,714.

To all whom it may concern:

Be it known that we, GRÄFIN MARIA VON LINDEN, professor in Bonn, ERNST MEISSEN, professor of medicine in Hohenhonnef, and 5 ARTUR STRAUSS, doctor of medicine in Barmen, citizens of the German Empire, residing, respectively, in Bonn, Hohenhonnef, near Bonn, and Barmen, Germany, have invented new and useful Improvements in 10 Pharmaceutical Compounds, of which the following is a specification.

We have found that lecithin compounds, such as lecithin, jecorin, cuorin, kephalin can be combined with inorganic or organic 15 copper compounds to complex copper compounds which have proved to be valuable remedies against infectious diseases, especially against tuberculosis.

The process for producing the new compounds consists in reacting with the copper compounds upon suspensions or solutions of lecithin or of its analogues, until the copper compounds used have disappeared.

In order to illustrate the new process more 25 fully the following examples are given, the parts being by weight:

Example 1: 1 part of the dry copper salt of cinnamic acid is triturated at a moderate temperature together with 2 parts of lecithin 30 until the blue color of the copper salt has disappeared and a uniform light green paste is obtained, which is the complex compound obtained from the cinnamate of copper and the lecithin. It is soluble with a light green coloration in ether and chloroform, insoluble in alcohol, and contains about 5.5 per cent. of copper.

Example 2: 1 part of copper chlorid, dissolved in alcohol, is added to an alcoholic 40 solution of 2 parts of lecithin. The copper compound of lecithin separates immediately

as an amorphous brownish-green mass, soluble in ether and olive oil with a light green coloration and insoluble in alcohol. It contains about 6 per cent. of copper and 3 per cent. of phosphorus.

The product obtained from kephalin (obtained from the brains of cows) and copper acetate is a greenish product containing 5.5-6 per cent. of copper. The complex copper compound obtained from jecorin (produced from the liver of horses) contains about 5.7 per cent. of copper and 2.1 per cent. of phosphorus.

We claim:

1. The new complex copper compounds of lecithin compounds, which are greenish products, soluble in ether and in chloroform, insoluble in alcohol, containing about from 5 to 6 per cent. of copper; and being valuable remedies against infectious diseases, substantially as described.

2. The new complex copper compound of lecithin, being a brownish-green product soluble in ether and olive oil with a light green coloration, containing about 6 per cent. of copper and 3 per cent. of phosphorus; being a valuable remedy against infectious diseases, substantially as described.

In testimony whereof we have hereunto set our hands in the presence of the subscribing witnesses.

GRÄFIN MARIA VON LINDEN. [L. S.]

ERNST MEISSEN. [L. S.]

ARTUR STRAUSS. [L. S.]

Witnesses to signatures of Gräfin Maria von Linden and Ernst Meissen:

LOUIS VANDORY,

BESSIE F. DUNLAP.

Witnesses to signature of Artur Strauss:

HELEN NUFER,

ALBERT NUFER.
